UNITED STATES PATENT OFFICE.

FRANCIS K. FASSETT, OF DAYTON, OHIO.

DOOR HANGER.

1,418,549.

Specification of Letters Patent. Patented June 6, 1922.

Application filed June 22, 1914, Serial No. 846,450. Renewed October 25, 1921. Serial No. 510,290.

To all whom it may concern:

Be it known that I, FRANCIS K. FASSETT, in the several views. a citizen of the United States, residing at Dayton, in the county of Montgomery and 5 State of Ohio, have invented a new and useful Improvement in Door Hangers, of which the following is a specification.

My invention relates to door hangers of the type wherein rubbing contacts are, as 10 far as possible, replaced by rolling contacts, and one of the objects of the invention is to confine the rubbing contacts to points where very little pressure is sustained. Another object is to provide that such metallic parts 15 as have rubbing contact with non-metallic parts shall also have rolling contact with metallic parts, whereby they will receive a planishing effect in the normal operation of the hanger. Another object is to provide 20 simple and effective means for attaching the door to the hanger after the latter is in place, by which the door can also be raised or lowered, and plumbed. Another object is to construct the hanger in such manner that the 25 door may hang plumb without putting unequal strains on the hanger parts, even though the parts are not perfect, or are imperfectly installed. Another object is to construct a hanger in such manner that 30 drawn steel can be used to a great extent, and casting nearly, if not wholly, eliminated.

In the accompanying drawings,

Fig. 1 is an elevation of a hanger and track with part of a door attached.

Fig. 2 is a plan of the hanger shown in Fig. 1.

Fig. 3 is a transverse section on line 3—3 Fig. 1.

Fig. 4 is a perspective view of the link.

40 Figs. 5 and 6 are details showing two ways of constructing the rider.

Fig. 7 is a modified form of link.

Fig. 8 is an elevational view, partly in section, of a hanger similar to that shown in 45 Fig. 1, but having its rollers coupled together by the type of link shown in Fig. 7;

Fig. 9 is an elevation of another form of hanger embodying the same principles as Fig. 1.

50 Fig. 10 is a plan of the hanger shown in Fig. 12.

Fig. 11 is a transverse section on line 14—14, Fig. 12.

55 Fig. 12 is the link used in this type of hanger.

Similar numerals refer to similar parts in the several views.

Referring now to Figs. 1, 2, 3 and 8, the track 25 is of a well known form, and the various ways in which it may be supported 60 are so well known that it is not necessary to show any of them. There are two pairs of wheels 26, each pair being connected by an axle 27 that slips with reasonable freedom into holes bored in the wheels, two wheels 65 and an axle forming a rolling element. The parts of the axles entering the wheels are turned down, forming shoulders (see the axle lying in the recess in the link shown Fig. 4) to prevent the axle getting out of 70 place. A rectilineal bar 28, called herein-after the rider, rests upon the axles between the wheels, and pendants 29 riveted to the ends of the rider pass between the troughs of the track, terminating in loops 30. Angle 75 bolts 31 are hooked into the loops and attached to the door by nuts, as shown in Figs. 1, 3 and 8. In the structure shown in Figs. 1 and 2, stirrups 32 secured to the rider carry a link 33, which, having apertures 34 80 to receive the axles, acts as a spacer to maintain an equal distance between the pairs of wheels. In Fig. 8 the style of link shown in Fig. 7 is used. In this type of link the apertures 34, instead of being mere notches 85 cut in the edge of the link, as in Fig. 4, are round holes bored so near as to cut through the edge and form narrow slots through which the axles protrude slightly, but leaving enough of the material to nearly surround axle and thereby form a support for the link. The stirrups 32 are then unnecessary. In either form of link the longitudinal slots 35 permit the rider to move with 90 reference to the wheels until one or the other 95 of the pendants strike the axle.

The operation of the hanger is easily understood; it is, in fact, almost obvious: When the door is moved, friction between the rider and axles tends to carry the axles 100 with it, which tendency causes the wheels to rotate. As the movement of the door continues the wheels roll along in the troughs of the track while a similar action takes place between the rider and axles, resulting 105 in the rider moving forward with reference to the axles. By the time the door has moved a given distance, depending on the relative diameters of the wheels and axles, the rear pendent will collide with the rear 110

axle. It is plain therefore that the link must be of such length as to permit of the required movement of the door without the movement of the wheels being restricted by the pendants. In addition to spacing the wheels the link keeps the axles parallel and prevents displacement of the wheels should they encounter an obstruction, such as a rough place in the track.

10 The freedom of the axles in the wheels permits the latter to move laterally with reference to each other and thus find the lowest point in the troughs of the track, and their treads being formed on a smaller radius than that of the troughs, insures perfect freedom from rubbing friction between the wheels and track. This feature is principally useful where the hanger is newly installed, as with the first few movements of the door to and fro the wheels find their places and thereafter the axles and wheels are likely to operate much as though they were integral. But this initial self adjustment is a valuable function and contributes very materially to 25 the remarkable freedom of movement and noiselessness that characterizes this hanger; the hubs of the wheels are made conical to prevent rubbing against the sides of the rider. With these provisions, and the perfect rolling action between the rider and axles,—cylinders rolling against a plane,—it is clear that there is no rubbing friction between the parts referred to. The link may be made of any one of a variety of substances, but I prefer hard wood thoroughly impregnated with a substance which will render it impervious to moisture and act to some extent as a lubricant. Paraffin has been 35 found satisfactory for this purpose. Because of its slight weight the friction between the link and axles is insignificant. An important factor in the reduction of friction at these points is the fact that the rolling action taking place between the rider and axles 40 gives to the latter a hard, bright surface.

The rider shown in Fig. 5 is composed of two flat strips of steel with the pendants 29 riveted between them, while the one shown in Fig. 6 is a solid square bar. When this 50 form is used slots have to be milled in the ends to receive the pendants. The two part rider is satisfactory for any but very heavy or wide doors. Another feature which contributes very much to the success of this 55 type of hanger is the manner of attaching it to the door. The loops 30 are capable of turning on the angle bolt so as to allow the rider to rest squarely on the axles. This prevents a tendency which the rider might 60 have to run to one side and hug the wheel hubs if the rider were tilted more or less, which it might be if secured to the door rigidly.

The structure illustrated in Figs. 9 to 12 65 inclusive embodies the principles already

described in a different form. A single track 50 is secured to the wall by any well known means, and grooved wheels 51, having axles 52, carry a rider composed of parallel strips 53—53, one strip resting on each of the 70 axles. The strips are united by screws 54 passing through spreaders 55, and also by the upper ends of the pendants 56 which, being formed into a U shape are riveted to the strips. The lower ends of the pendants 75 are bent inwardly and provided with open slots 57 to receive the bodies of bolts 58. A recess 59 is formed in each pendent of such size as to allow the head of the bolt to pass through, thereby enabling the door to be attached after the hanger is in place and the bolts screwed into or otherwise attached to the door. The recess extends a short distance on the horizontal part of the pendent, as will be seen in Fig. 16. A clip 60 having 80 upturned flanges 62, and a slot which reaches from one flange to the other (not shown) is strung on each bolt above the jamb nut 63, and after the bolts are in place in the slots 57 the clips are pushed up into place, the flanges 62 serving to close the ends of slots 90 57. After the nuts 63 are screwed up against the clips, or even near them, it is impossible for the bolts to slip out of the pendent slots. The threads of the bolts may be slightly 95 mutilated after the nuts are screwed up, to prevent the nuts working far enough down to let the bolts out.

In this hanger the link is composed of two strips 65 fastened together by screws and 100 spreaders 66. The apertures 67 are formed so as to afford support for the link, as before described, but if desired, however, the stirrups before described may be used for supporting it. The links engage the part of the axles which is engaged by the rider as in the type of hanger first described, which not only economizes space but reduces friction as has been explained. The flanges of the wheels are made to flare, and the hubs 105 are conical, both to eliminate rubbing against the sides of the members they come in contact with. The treads of the wheels are crowned so as to insure a balanced strain 110 on the hanger. The screws which enter spreaders 66 may if desired be loose in the links so as to allow the links to adjust themselves to conditions.

It will be noticed that the axles are permitted to run almost to the ends of the rider, 120 but the axle of one wheel is prevented from going beyond the end by the other wheel colliding with the spreader 55. In this way the wheel base of the hanger may be very long in proportion to the width of the door. 125 The heads of the bolts being quite close to the lower edge of the track prevents derailment of the hanger.

It is not to be understood that either embodiment of my invention is preferred, as 130

each has advantages which commend its use under certain circumstances. Either type is susceptible to modification without departing from the substance or exceeding the 5 scope of the appended claims.

What I claim is as follows:

1. In a door hanger, a track, wheels arranged to roll thereon, said wheels having axles, a link mounted on the axles for the 10 purpose of connecting the wheels together, the apertures for the axles being bored so near the upper edge of the link that lateral slots are formed which expose narrow portions of the axles but enclose enough there- 15 of to support the link, and a rider resting on said exposed portions.
2. In a door hanger, a track having a double tread, wheels to roll thereon, said wheels being arranged in pairs, one wheel rolling 20 on each tread, and connected by an axle, a link mounted on the axles so as to connect the pairs of wheels together, the apertures for the axles being bored so close to the upper edge of the link that lateral slots are 25 formed which expose narrow portions of the axles but enclose enough thereof to support the link, and a rider resting on said exposed portions of the axles.
3. In a door hanger, a track having a double tread, wheels to roll thereon, said wheels being arranged in pairs with one wheel resting 30 on each tread; each wheel being bored axially, axles comprising end portions which fit freely in the wheel bores, and an enlarged 35 central portion, the steps at the points where the diameters change forming shoulders which prevent the axles slipping an excessive distance in either direction but permitting sufficient endwise movement to allow the ax- 40 les and wheels to accommodate themselves to conditions, a link mounted on said central parts of the axles to connect the pairs of wheels together, the apertures for the axles being bored so close to the upper edge of the 45 link that lateral slots are formed which expose narrow portions of the axles but enclose enough thereof to support the link, and a rider resting on said exposed portions of the axles.
5. In a door hanger, a track, wheels arranged to roll thereon, said wheels having

axles, a link whereby said wheels are coupled together, said link having recesses in its upper edge in which the axles lie and rotate as the wheels roll along the track, said recesses being open at the top so as to expose the upper parts of the axles; a rider resting on said exposed parts of the axles, means for attaching the rider to a door, and means for supporting the link. 55

6. In a door hanger, a track having a double tread, wheels to roll thereon, said wheels being arranged in pairs, one wheel of each pair rolling on each tread and connected by an axle, a rectilinear rider resting on said 60 axles; means for connecting the rider to a door, comprising members to be rigidly attached to the door and a hinge like connection between said members and the rider, which permits of a rocking movement of the 65 rider with reference to the door on an axis parallel to the track, so that the rider may seat itself squarely on the axles; a link under the rider and connecting the axles together, means for supporting the link and 70 means for confining its engagement with the axles to the zones which sustain the rider. 75

7. In a door hanger, a track having a double tread, wheels to roll thereon, said wheels being arranged in pairs with one wheel resting 80 on each tread, each wheel being bored axially; axles comprising end portions which fit freely in the wheel bores and an enlarged central portion, the steps at the points where the diameters change forming shoulders 85 which prevent the axles slipping an excessive distance in either direction but permitting sufficient endwise movement to allow the axles and wheels to accommodate themselves to conditions; a link whereby the axles 90 of the pairs of wheels are coupled together, said link having recesses in its upper edge to receive the axles, the tops of the recesses being open so as to expose the tops of the axles, a rider resting on said exposed tops 95 of the axles, and means for supporting the link.
